UNITED STATES PATENT OFFICE.

HENRY ARTHUR BETTNEY, OF CARLTON, ENGLAND.

KNITTING-MACHINE.

SPECIFICATION forming part of Letters Patent No. 634,843, dated October 10, 1899.

Application filed December 24, 1897. Serial No. 663,377. (No model.)

To all whom it may concern:

Be it known that I, HENRY ARTHUR BETTNEY, a subject of the Queen of Great Britain, residing at Carlton, in the county of Nottingham, England, have invented certain new and useful Improvements in Knitting-Machines, of which the following is a specification.

This invention relates to improvements in and applicable to circular-knitting machines fitted with bearded needles and bladed knitting-wheels, the object of the present invention being the provision of improved means by which a splicing-thread may be inserted and withdrawn with certainty and accuracy at any predetermined needle and at any particular course, means by which the splicing-thread may be held in or out of its knitting position for any number of courses or parts of courses, means for cutting the thread and holding the cut end when the thread is thrown out of action, and means for automatically controlling the action of the aforementioned mechanisms.

In the accompanying drawings, Figure 1 is an elevation, partly in section, of a knitting-machine, showing the improved splicing apparatus. Fig. 2 is a sectional plan at A A, Fig. 1, partly-broken to show the underneath mechanisms. Fig. 3 is a part plan of a splicing mechanism, showing a spring-lever arrangement. Fig. 4 is a front elevation of a splicing-thread carrier, wheel, cutter, and connected parts. Fig. 5 is a part side elevation of Fig. 4, showing more particularly the thread cutters and holder. Fig. 6 is a plan of Fig. 4. Fig. 7 is a series of drawings showing the shape of the blades in the splicing-blade wheel; and Figs. 8, 9, 10, and 11 are drawings showing the splicing-thread carrier, cutter, and trapper in different positions.

The splicing-thread-carrier mechanism shown in Figs. 4, 5, and 6 is arranged relatively to the machine as shown in Fig. 1, and comprises a blade-wheel 1, which is carried by a bracket 2 of the usual description and performs the function of laying a thread on the needles similarly to bladed wheels of the ordinary description. Attached to the bracket

2 is a plate 3, to which the fixed cutter 4 is connected by a spring 5. On the inner side of the plate 3 there is fitted a slide 6, to which the movable holder 7 and movable cutter 8

are attached. The slide 6 is fitted with pins 9, which slide in slots 9^a and is actuated by a lever 10 from the splicing-thread-carrier axle 55 11. The lever 10 is pivoted at 12 on a bracket 13, which is carried by the same piece 2^a as the bracket 2, and it is embraced by the forked end of a lever 14, which is loosely mounted on the axle 11. The boss of the lever 14 is 60 cut, as shown at 15, to correspond with a similarly-cut boss 16, which is fast on the axle 11 and is arranged to actuate the lever 14 and its connected parts after the thread has been moved by its guide 17 into the position shown 65 in Fig. 9. The carrier 17 is firmly attached to the axle 11, which is also fitted with a lever 18, provided with a truck 19 and a spring 20 for holding the truck in contact with the cam-truck lever. 70

The number of needles in the knitting-head must be exactly divisible by the number of blades in the wheel 1, and as the splicing-thread is thrown into and out of action at opposite ends of a diameter of this wheel the 75 number of needles upon which a splicing-thread is laid must be equal to half the number of blades in the wheel or some odd multiple of this number. The shape of the blades at which the thread is thrown into and 80 out of action is shown at Fig. 7, which represents consecutive blades in a wheel revolving in the direction of the arrows. The row A shows the blades at which the thread x is thrown into work. At blade a thread x is 85 out of work, and as the wheel revolves the thread is moved across the blades until it enters the groove in blade g, which is the first blade to lay the thread on the needles. The blades h and i then guide the thread to the 90 usual knitting position, as shown on blade j. The row B shows the shape of the blades at which the thread x is thrown out of work. The thread is moved from the knitting position shown on blade a' to the groove in 95 blade e', which is the last blade to lay the thread on the needles. The thread is then moved over the blades f', g', h', and i' until it is out of work in the position shown relatively to the blade j'. 100

Referring to Figs. 1, 2, 3, and 4, the needles 21 are carried by a cylinder 22, which is mounted and actuated in the usual way. Fixed to the machine frame 27 with each

group of knitting-wheels there is a splicing-wheel and thread-carrier, which are fitted as already described. The cam-truck 19 on the lever 18 is held by the spring 20 in contact with a cam truck lever 23, which is fulcrumed at 24 and fitted with a truck 25, which is held in contact with the cam 26 when the splicing apparatus is at work by the spring 20 through the lever 18. The length of the raised portions of the cam 26 corresponds to the length of the unspliced portions of a course, and as the cam 26 revolves with the needle-cylinder the splicing-thread is thrown in and out of action, according to the number of rises on the cam.

The mechanism for holding the splicing-thread out of action altogether comprises a catch which prevents the lever 23 following the cam 26. The catch-lever 40 is pivoted at 41 to the under side of the frame 27 and is provided with a pin 42 for holding the lever 23 out of action. The lever 40 is also connected to a ring 28, which is capable of a limited circular motion which is obtained from the pattern-chain 32. This pattern-chain is carried by a double-flanged wheel 33^a, which is attached to a ratchet-wheel 34. On the same axle there is another ratchet-wheel 35 with the same number of teeth as the wheel 34, and fastened to the wheel 35 there is a third ratchet-wheel 36, having one tooth for every four teeth in the wheels 34 and 35. The ratchet-wheels are actuated by a lever 38, which is fulcrumed at 39 and operated by a cam 39^a on the needle-cylinder. The lever is fitted with two clawkers 37 and 37^a, the former acting upon the teeth of the wheel 35 to rotate the same and the wheel 36, which is fastened thereto. The clawker 37^a is used for operating the wheel 34 and the connected chain-wheel 33^a and acts upon the wheel 34 once in every four oscillations of the lever 38. For the other three oscillations the clawker 37^a is held clear of the wheel 34 by the wheel 36, upon which it rests. The wheel 34 is thus operated one tooth at every four revolutions of the needle-head, and a short pattern-chain is used; but an ordinary ratchet-wheel arrangement with a longer chain may be used, if desired.

The ring 28 is fitted to move on the under side of the frame 27 and, near the pattern-chain, is fitted with an adjusting-screw 29, which is held in contact with the lever-arm 30 by means of a spring 30^a. The other arm 31 rides upon the chain 32 and when raised by a pattern-piece is held in its raised position by a catch 33 until another piece strikes the catch 33 and releases the lever 31, which allows of the ring 28 to be moved by its spring. The movements given to the ring 28 are timed to take place when the raised part of the cam 26 is opposite the lever 23, the splicing mechanism being thus thrown into and out of work without a jerk.

In a machine fitted with two or more feeders and splicing the same portion of each

course it is necessary that the splicing-thread should be thrown into action at the same needle. To enable this to be done with the same mechanism, the lever 23 is made with a hooked end, as shown at Fig. 3, and the outer end of the lever 40 is fitted with springs 45 and 46, which are placed between pins 44 on the ring 28. This arrangement may be used with all the splicing mechanisms, and when this is done the pattern-chain may be actuated at any part of the revolution of the needle-cylinder. The ring 28 is moved as already explained, and when moved in the direction of the arrow 43 the spring 45 is placed in tension, but is prevented from moving the lever 40 by the hook on the end of the lever 23. When, however, the raised part of the cam comes opposite the lever 23, it raises the same sufficiently to allow of the spring 45 moving the lever 40 clear of the lever 23. When the ring 28 is moved in the opposite direction, the lever 40 is moved into a position to hold up the lever 23, and when this is raised by the cam 26 its hook is forced past the pin on the lever 40, which is then moved under the hook by the spring 46.

The number and arrangement of the splicing-thread mechanisms to each head may be varied. Thus in a three-feeder head splicing three different portions of the same course the cam 26 may have three rises and the three splicing-threads be thrown into and out of action simultaneously. In a four-feeder head splicing two different portions of the same course the splicing-threads may be thrown into and out of action in pairs, the cam 26 having two raised portions.

When the herein-described mechanism is in operation and the splicing-thread is to be thrown out of action, the cam 26, through the levers 23 and 18, moves the carrier 17 from its knitting position, Fig. 8, to the position shown in Fig. 9 and the thread is moved between the cutters and holder, which then commence to move. The thread is first trapped by the holder 7, Fig. 10, and is afterward severed by the cutter 8, Fig. 11. When the thread is thrown into action, it is first moved to its knitting position and then released from the holder, the loose end being guided by the guide 21^a.

In addition to the parts herein described the machine is fitted with the usual knitting-wheels, thread-carriers, work-rollers, and other usual mechanisms.

What I claim as my invention, and desire to secure by Letters Patent, is—

1. In a circular-knitting machine, the combination of the needles, needle-cylinder, splicing-thread carrier and axle carrying the same, a lever on the said axle, a lever pivoted on the machine-frame and adapted to engage the lever on the axle, a cam on the needle-cylinder for actuating the splicing-thread carrier through the above-mentioned levers, a bladed wheel with certain blades cut out to form an inward lead, and other blades cut out to form

an outward lead to the splicing-thread, a stationary cutter and sliding cutter for severing the splicing-thread, a holder for holding the cut end of the thread, and mechanism for actuating and controlling the cutter and holder, constructed arranged and operating substantially as herein set forth.

2. In a circular-knitting machine, the combination of the needles, needle-cylinder, splicing-thread carrier, an axle therefor, levers and cam for operating the same, a bladed wheel with cut blades, a fixed cutter-blade, a spring carrying the same; a movable cutter-blade, a lever actuating the same, pivoted on the thread-carrier axle, a cut boss on the said lever, a cut collar fast on the splicing-thread-carrier axle adapted to engage said cut boss, and a thread-holder attached to the movable cutter and moving therewith, constructed, arranged and operating substantially as set forth.

3. In a circular-knitting machine, the combination of the needles, the needle-cylinder, a splicing-thread carrier, means for actuating the said carrier, a catch arranged to hold such means out of action; a ring 28 capable of a limited circular motion adapted to move the said catch, and pattern-controlled mechanism regulating the movements of the said ring, substantially as set forth.

4. In a circular-knitting machine, the combination of the needles, the needle-cylinder, a splicing-thread carrier, a lever through which said carrier is operated, a second lever with which the first-mentioned lever has engagement and from which it is moved, a cam on the needle-cylinder for operating the said second lever, a catch for holding the second lever out of engagement with the cam, a ring 28 with which the catch is connected, and a pattern-controlled mechanism for operating the ring, substantially as set forth.

5. In a circular-knitting machine, the combination of the needles, the needle-cylinder provided with an operating-cam 26, a splicing-thread carrier, means worked by the said cam for operating the carrier, a catch-lever ar-

ranged to hold such means out of action, a movable, pattern-controlled member for operating the catch-lever, a spring connection 50 interposed between the said movable member and the catch-lever, and a hook carried by the means which operate the thread-carrier arranged to hold the catch-lever, the said parts being arranged substantially as set 55 forth, whereby when the said movable member is moved the spring is put under tension, but the catch-lever is held until the cam 26 comes into operation when it is released and the spring quickly moves the catch-lever. 60

6. In a circular-knitting machine, the combination of the needles, the needle-cylinder provided with an operating-cam 26, a cut-bladed wheel, a splicing-thread carrier for moving the splicing-thread into and out of 65 action, an axle carrying the said thread-carrier, operative connections for the said axle adapted to be intermittently worked by the said cam, a cutter and holder for the splicing-thread, and means for working the cutter and 70 holder from the splicing-thread-carrier axle, the said parts being arranged as that there is a certain amount of lost motion, whereby the movements of the said cutter-holder are subsequent to the movement of the carrier, 75 substantially as set forth.

7. In a circular-knitting machine, the combination of the needles, the needle-cylinder provided with the cams 26 and 39^a, a splicing-thread carrier, means operated by the cam 26 80 for working the said thread-carrier, a catch arranged to hold said means out of action, a ring capable of a limited circular movement adapted to move the said catch, a pattern-chain and operative connections by which 85 the said ring is moved, and a clawer-and-ratchet mechanism operated by the cam 39^a through which the pattern-chain is moved, substantially as set forth.

HENRY ARTHUR BETTNEY.
